The ornamental design for a terminal of a holder system for supporting mobile electronic devices and external articles, as shown and described.

DESCRIPTION

FIG. 1 is a perspective view of a terminal of a holder system for supporting mobile electronic devices and external articles showing my new design.

FIG. 2 is a top view thereof.

FIG. 3 is a bottom view thereof.

FIG. 4 is a left side view thereof.

FIG. 5 is a right side view thereof.

FIG. 6 is a front view thereof.

FIG. 7 is a rear view thereof.

FIG. 8 is a perspective view of a terminal of a holder system for supporting mobile electronic devices and external articles according to another example embodiment.

FIG. 9 is a top view of FIG. 8.

FIG. 10 is a bottom view of FIG. 8.

FIG. 11 is a left side view of FIG. 8.

FIG. 12 is a right side view of FIG. 8.

FIG. 13 is a front view of FIG. 8; and,

FIG. 14 is a rear view of FIG. 8.
